UNITED STATES PATENT OFFICE

BROWDER J. THOMPSON, OF SCHENECTADY, NEW YORK, ASSIGNOR TO GENERAL ELECTRIC COMPANY, A CORPORATION OF NEW YORK

AMPLIFYING APPARATUS

Application filed December 24, 1927. Serial No. 242,475.

My present invention relates to amplifying apparatus, and more particularly to circuit arrangements employed with electron discharge devices to obtain regenerative amplification with high frequency currents.

In the usual forms of regenerative circuit connections which are employed with electron discharge apparatus for obtaining a high degree of amplification it is known that if the apparatus is to be used to amplify a wide range of frequency the regenerative connections must be varied from time to time as the frequency to be amplified varies in order to obtain the best results. If the regenerative connection is adjusted to give the maximum degree of amplification without oscillations at the higher frequencies to be amplified then at the lower frequencies the degree of amplification obtained will be much less and adjustment must be made in order to obtain satisfactory results.

The object of my invention is to overcome this disadvantage and provide an amplifying system in which regenerative amplification is usefully employed and in which the degree of amplification which may be obtained will be substantially the same throughout the range of frequencies for which the system is intended to operate without any necessity for adjusting the regenerative connections as the frequency is varied.

To accomplish this result I provide two separate means for producing regenerative amplification, one of which is most effective at the higher frequencies and the other of which is most effective at the lower frequencies. By the proper initial adjustment of these instrumentalities it is possible to obtain a substantially uniform degree of amplification throughout the range of frequencies over which the system is designed to operate.

The novel features which I believe to be characteristic of my invention are set forth with particularity in the appended claims. My invention itself, however, both as to its organization and method of operation will best be understood by reference to the following specification taken in connection with the accompanying drawing in which I have indicated diagrammatically one circuit organi-

zation whereby my invention may be carried into effect.

I have indicated in the drawing an electron discharge device 1 of the four-electrode type having an electron emitting cathode 2, 55 an anode 3 and two grids 4 and 5. This device may be constructed in any desired way so that the electron stream in flowing from the cathode to the anode 3 passes successively the two grids 4 and 5. The grid 4 is connected to a portion of the battery 6 so that it has impressed thereon a suitable positive potential with reference to the cathode to enable it to operate efficiently as a space charge grid. The grid 5 is employed in the usual manner to 60 control the electron stream through the device. In the present case I have indicated a tuned input circuit 7 with a grid condenser 8, and grid leak 9, whereby the device may operate as a detector of high frequency currents 65 impressed upon it from the antenna 10. The output circuit of the device includes all of the battery 6, the telephone receivers 11 and a tickler or feed-back coil 12 which is inductively coupled to the input circuit so as to 70 provide a feed-back of energy for the purpose of giving regenerative amplification. 75

I have also provided in the circuit of the space charge grid 4 an impedance load consisting of an inductance 13 and a capacity 14 80 connected in parallel. These are so related to one another that at the lowest frequency which the circuit is intended to amplify the impedance in the space charge grid circuit is slightly capacitive. It is well known that 85 when a load is placed in the circuit of a space charge grid the potential of that grid will vary as the current through the device varies but that the changes in this potential will be in the opposite direction to the changes 90 in potential of the plate or anode. By reason of the capacity between the two grids a feed-back action may be produced between the two grids which will affect the potential 95 of the control grid 5 and thereby modify the amplifying action of the device. In order that this potential fed back through the capacity between the grids may assist in producing amplification the reactance of the space charge grid circuit must be capaci- 100

tive, therefore, as above stated, I adjust the space charge grid so that it has a sufficient capacitive reactance to produce the desired degree of amplification when the frequency impressed upon the circuit is the lowest which the circuit is intended to amplify. As the frequency increases the effect of the feed-back decreases because of the fact that the capacitive reactance becomes less and therefore the potential changes of the space charge grid become less.

The feed-back coil 12 on the other hand is adjusted so as to give the maximum degree of amplification desired at the highest frequency which the system is intended to amplify. If it remains fixed at this point the regenerative amplification due to the feed-back coil will decrease as the frequency applied to the system decreases. Thus it will be seen that the two means provided for producing amplification vary in opposite directions as the frequency varies. As a result it is possible by the joint action of the two means to obtain a substantially uniform degree of regenerative amplification over the entire range of frequencies at which the apparatus is designed to operate.

While I have shown and described the preferred embodiment of my invention it will of course be understood that many modifications in the circuit arrangement employed as well as in the specific form of apparatus used, may be made without departing from the scope of my invention as set forth in the appended claims.

What I claim as new and desire to secure by Letters Patent of the United States is:

1. The combination with an electron discharge device having an electron emitting cathode and anode and two grids which are successively passed by the electron stream of separate circuits connecting the cathode with each of the other electrodes, and two separate means for producing regenerative amplification by the action of one of said grids, one of said means being most effective at the higher frequencies and other means being most effective at the lower frequencies at which the circuits are intended to operate.

50 2. The combination with an electron discharge device having an electron emitting cathode and anode and two grids which are successively passed by the electron stream, of separate circuits connecting the cathode with each of the other electrodes, and an inductive feedback from the anode circuit to the circuit of one grid and a capacitive feed back from the other grid to the first grid.

3. The combination with an electron discharge device having an electron emitting cathode and anode and two grids which are successively passed by the electron stream, of separate circuits connecting the cathode with each of the other electrodes, means for impressing high frequency oscillations on the

circuit of one grid, a feedback connection from the anode circuit to the grid circuit upon which the oscillations are impressed, and a second feedback to that grid circuit from the other grid.

4. The combination with an electron discharge device having an electron emitting cathode and anode and two grids which are successively passed by the electron stream, of separate circuits connecting the cathode with each of the other electrodes, means for impressing high frequency oscillations on the circuit of one grid, an inductive feed back connection from the anode circuit to grid circuit upon which high frequency oscillations are impressed, and means for producing a capacitive reactance on the circuit of the other grid.

5. The combination with an electron discharge device having an electron emitting cathode and anode and two grids which are successively passed by the electron stream, of separate circuits connecting the cathode with each of the other electrodes, and two separate means for producing regenerative amplification by the action of the grid nearest the anode, one of said means being most effective at the higher frequencies and the other means being most effective at the lower frequencies at which the circuits are intended to operate.

6. The combination with an electron discharge device having an electron emitting cathode and anode and two grids which are successively passed by the electron stream, of separate circuits connecting the cathode with each of the other electrodes and an inductive feed back from the anode circuit to the circuit of the grid nearest the anode, and a capacitive feed back from the other grid to the grid nearest the anode.

7. The combination with an electron discharge device having an electron emitting cathode and anode and two grids which are successively passed by the electron stream, of separate circuits connecting the cathode with each of the other electrodes, means for impressing high frequency oscillations on the circuit of the grid nearest the anode, a feed back connection from the anode circuit to the grid circuit upon which oscillations are impressed, and a second feedback to that grid circuit from the other grid.

8. The combination with an electron discharge device having an electron emitting cathode and anode and two grids which are successively passed by the electron stream, of separate circuits connecting the cathode with each of the other electrodes, means for impressing high frequency oscillations on the circuit of the grid nearest the anode, an inductive feedback connection from the anode circuit to the grid circuit upon which high frequency oscillations are impressed, and

means for producing a capacitive reactance in the circuit of the other grid.

9. The combination with an electron discharge device having an electron emitting cathode and anode and two grids which are successively passed by the electron stream, of separate circuits connecting the cathode with each of the other electrodes, means for impressing high frequency oscillations on the circuit of the grid nearest the anode, a fixed inductive feed back connection from the anode circuit to the grid circuit upon which high frequency oscillations are impressed, and means for producing a capacitive reactance in the circuit of the other grid, which increases in value as the frequency of the oscillations impressed upon the circuit decreases.

In witness whereof I have hereunto set my hand this 23rd day of December, 1927.

BROWDER J. THOMPSON.
